UNITED STATES PATENT OFFICE.

WILLIAM F. SIEGENER, OF PHILADELPHIA, PENNSYLVANIA, ASSIGNOR TO
HERRMAN DIENELT, OF SAME PLACE.

DESIGN FOR A PAPER DOILY.

SPECIFICATION forming part of Design No. 35,016, dated August 27, 1901.

Application filed August 1, 1901. Serial No. 70,557. Term of patent 7 years.

To all whom it may concern:

Be it known that I, WILLIAM F. SIEGENER, a citizen of the United States, residing in Philadelphia, Pennsylvania, have invented and produced a certain new and original Design for a Paper Doily, of which the following is a specification.

My design for a paper doily is shown in the accompanying drawing.

My design comprises as its essential features a plain central portion surrounded by certain rows of perforations and perforated figures adjacent to the scalloped edge of the doily.

1 represents a scalloped edge extending around the four sides of the doily, and 2 represents a row of circular perforations at the opposite side of the border and immediately surrounding the plain central portion 3. Ad-

jacent to the scalloped edge is a row of figures 4, consisting of a central circular perforation and a series of wedge-shaped perforations surrounding the same and projecting toward said central perforation, the

whole surrounded by a series of smaller circular perforations which form an approxi-

mate square. Adjacent to the row of perforations 2 is a row of figures 5, consisting of a central circular perforation and a series of wedge-shaped perforations projecting toward 30 said central perforation. Inside the scalloped edge is a row 6 of circular perforations following the contour of said edge, and at the corners of the doily are the figures 7, formed of a central circular perforation and a concentric row of smaller circular perforations. Rows 8 of circular perforations extend from 35 said figures 7 to the corners of the rows of perforations surrounding the plain central portion 3.

Having thus described my invention, I claim and desire to secure by Letters Patent—

The design for a paper doily, substantially as described and as shown in the accompanying drawing.

In testimony whereof I have signed my name to this specification in the presence of two subscribing witnesses.

WM. F. SIEGENER.
